UNITED STATES PATENT OFFICE.

CHARLES E. TITUS, OF WARREN, PENNSYLVANIA.

BOX-PASTING MACHINE.

SPECIFICATION forming part of Letters Patent No. 415,660, dated November 19, 1889.

Application filed May 15, 1889. Serial No. 310,899. (No model.)

To all whom it may concern:

Be it known that I, CHARLES E. TITUS, a citizen of the United States, residing at Warren, in the county of Warren and State of Pennsylvania, have invented new and useful Improvements in Box-Pasting Machines, of which the following is a specification.

It is the purpose of my invention to provide a simple and easily-operated machine for applying a paper or cloth binding or strengthening strip to the angles of boxes either for the purpose of ornamentation or for securing the angles and stiffening the box. It is my object to so organize the mechanism that the strip may be fed directly through the paste-reservoir, where it receives the paste upon one side or surface, whence it is carried to the point of application, and automatically guided to the angles of the box, which revolves upon a suitable support.

It is one purpose of my invention to provide means whereby cheap pasteboard boxes may be quickly, neatly, and economically constructed, having uniform size, accurate shape, and a considerable strength, said invention being also applicable to the trimming of cigar and other boxes, or to the manufacture and ornamentation of boxes of any kind, form, or dimensions, provided the size does not greatly exceed that of the ordinary box for cigars and small articles of merchandise of various descriptions.

The invention consists in the several novel features of construction and combinations of parts hereinafter set forth and claimed.

Referring to the accompanying drawings, Figure 1 is a perspective view of the entire machine. Fig. 2 is a front elevation, partly in section. Fig. 3 is a plan view of the same. Fig. 4 is an elevation taken from the left-hand end of the machine. Fig. 5 is an elevation taken from the right-hand end. Fig. 6 is a perspective view of the form used in pasting covers.

In the drawings, the reference-numeral 1 designates the base-plate or frame of the machine, which may be mounted on any suitable supports, such as foot-pieces 2^b. From the rearwardly-extending portion of this frame rises a vertical plate 2, having a foot-flange 3, which is provided with apertures to receive bolts 4, the latter passing through slots 5 in

the base-plate and receiving nuts upon their lower ends, whereby the plate 2 may be adjusted laterally or in a direction parallel with the front edge of the base-plate. Slots 2^a are also formed in the foot-flange 3 at right angles with the slots 5, whereby a forward and rearward adjustment of the plate or bracket 2 may be effected. Upon the upper end of the plate 2 is formed a horizontal plate 6, which joins a vertical plate 7, rising from the base of the plate 2 and standing at right angles with the middle portion thereof, to which it is joined. The plate 7 preferably increases in width as it rises, and projects some distance above the horizontal piece 6.

Upon the face of the vertical plate 2, which stands at right angles with the front of the frame, are formed two vertical flanges 8, between which is inserted a paste-cup 9, formed of sheet metal or other suitable material, and provided with a lip 10 upon its rear wall, which hooks over a similar but upwardly-turned lip 12 upon the plate 2. This paste-cup may be of any desired form and size; but at its bottom it is diminished in width to or nearly to the width of the paper or cloth strip to be applied to the box. The bottom of the cup is formed of an upwardly-curved strip 13, and slots 14 are formed in the side walls of the cup to permit the passage of the strip. These slots are preferably formed by leaving the extremities of the curved bottom piece unattached, and beneath the exit-opening for the strip is arranged a set-screw, tapped through a bracket 15 and bearing against the flexible end of the bottom piece, whereby the latter may be adjusted to exactly the proper point to permit the passage of the strip, control the tension thereon, and remove the surplus paste. The strip is taken from a roll or coil 16, mounted on an axis 17, projecting from the plate 2 behind the cup, and upon this axis is mounted a tension-plate 18, which is forced against the roll or coil by a jam-nut 20.

Upon the front of the base-plate 1 is formed a narrow horizontal plate of suitable length, having upon its parallel edges narrow overhanging flanges 22. At the right-hand extremity of this way is mounted a standard or post 23, having foot-flanges passing beneath the flanges 22 and capable of a limited longi-

tudinal adjustment in the way 21, this movement being limited by a stud depending from the foot of the standard and passing through a slot 24 in the way. A nut screwed on the 5 lower end of this stud locks the standard at any point to which it is adjusted.

In the upper end of the post 23 is formed a bearing 25, which receives a shaft 26, lying parallel with the way 21, and having upon its 10 end a crank 27. Upon the other end of said shaft is mounted a rectangular form 28, of the size and shape of the box to be pasted, said form being provided with resting lugs or flanges 29, adapted to support the edges of 15 the box when the plane of its bottom is in the plane of the flat face 30 of the die. In the way 21 is arranged a movable standard 31, having journaled in its upper end a holding disk or plate 32, which stands opposite 20 the central portion of the vertical face of the die and parallel therewith. Passing through the extended foot-piece 33 of the standard 31 is a locking-bolt 34, which engages an opening 35 in the way 21, this engagement being 25 effected at the moment when the holder is pressed closely up against the box-bottom as it lies against the face 30 of the form. This bolt is drawn by a spring-actuated lever 36, pivoted on a lug 37, and connected to an eye 30 on the bolt, the spring 38 operating the lever to throw the bolt into the opening 35 automatically.

In the manufacture of pasteboard boxes the blanks for the body portions are cut to uniform size and are then scored at the angles, 35 thereby permitting the board to be brought to the required rectangular shape. It is then placed upon the form, with its free ends inserted beneath spring-clips 39, by which they 40 are firmly held. The square or other shaped board composing the bottom of the box is then laid against the vertical face of the form, and the support comprising the disk or plate 32 is moved up and forced against it. The operator 45 then seizes the end of the strip projecting from the bottom of the paste-cup and draws it forth from the latter, passing it beneath the die, which is adjusted in such manner that about half of the width of the strip 50 overlies the body portion of the box. Applying the pasted surface thereto the crank 27 is turned until the strip is turned around the body of the box and lapped slightly at its ends, whereupon it is cut off and the extremity 55 neatly pressed in place. The operator now, by a proper manipulation of the projecting edge of the strip, brings it over upon the edges of the bottom part, turning the form slowly to present each side in succession, and, if preferred, the projecting margin may be notched or cut at the angles, to give a neater and smoother appearance. The entire operation is quickly and easily performed and requires no special skill or experience, since the box-blanks are so accurately held and the strip so 60 guided as to demand no attention from the operator. The meeting edges or ends of the

body-blank are pasted by a short strip, which may be taken from a separate paste-cup 40, mounted upon the upper part of the plate 7. 70 This cup is the counterpart in all substantial particulars of the one described, but is arranged for convenience at right angles with the latter, the strip being taken from a bearing 41 on the plate 7, provided with suitable 75 tension devices. The short strips pasted by this cup are cut and applied by hand after the bottom has been attached, although the order of the two operations may be reversed, if desired. The covers are pasted by the device shown in Fig. 6, which may be substituted for the form, the shaft 26 being unscrewed from the latter to permit its removal, and then screwed into a threaded central opening in the form-stock 42, carrying the 80 form 43, which receives the cover-blank. The form may be formed of sheet metal having four flanges 44 of about the width of the edges of the cover. In use the strip is applied to the cover in precisely the same manner as it 85 is applied to the body and bottom of the box.

By this invention boxes of any kind and of all shapes may be quickly, cheaply, and neatly pasted or ornamented in any desired manner and by persons possessing no special skill or 90 experience in the art.

It will be seen that by the construction of the paste-cup the flexible strip passes over the curved bottom plate and is thoroughly smeared with paste upon its exposed surface, 10 while it receives little, if any, paste upon the surface adjacent to said bottom plate.

What I claim is—

1. In a box-pasting machine, the combination, with a support for the trimming-strip, 10 and a rotating form for carrying the box, of a paste-cup having the lower ends of two oppositely-arranged side walls provided, respectively, with a slot and a bottom piece in the base of the cup, which supports the trimming-strip between the slots, substantially as described.

2. In a box-pasting machine, the combination, with a support for the trimming-strip and a rotating form for carrying the box, of a paste-cup having two oppositely-arranged side walls provided, respectively, with a slot and a bottom piece having a flexible end which is adjustable vertically to and from the upper edge of the exit-slot, substantially 12 as described.

3. In a box-trimming machine, the combination, with a support for the trimming-strip and a paste-cup, of a horizontal supporting-plate, and two standards having their lower ends movable to and from each other in ways on the supporting-plate, one standard having at its upper end a support for pressing on the box-bottom and the other having at its upper end a rotary shaft carrying a form to enter 13 within and carry the box, substantially as described.

4. In a box-pasting machine, the combination, with a rotary form supporting the box

and provided with resting-lugs and spring-clips holding the ends of the body-blank, of a paste-cup through which the strip of paper or other material is drawn, and a tension device acting upon the coil or roll from which said strip is taken, substantially as described.

5. In a box-pasting machine, a paste-cup having in its bottom a curved plate the extremities of which are unattached to the walls of the cup to form entrance and exit openings for a flexible strip drawn through said cup and over the curved bottom plate, substantially as described.

6. In a box-pasting machine, a paste-cup having an upwardly-curved plate in its bottom, the ends of said plate being detached from the walls of the cup to form passages for a flexible strip lying on the curved bottom plate, in combination with a set-screw 15 tapped through a bracket underhanging the exit of the plate and bearing against the same, substantially as described.

7. In a box-pasting machine, the combination, with a rotary form for the box mounted 20 on an adjustable support, of a movable support for the box-bottom, a paste-cup having a curved bottom plate and provided at each

end of said plate with passage-openings for a flexible strip, and a support for the paste-cup adjustable in two directions parallel with and 30 at right angles to the adjustments of the rotary form, substantially as described.

8. In a box-pasting machine, the combination, with an adjustable standard, of a shaft carrying a rotary form having resting-lugs 35 and spring-clips, a movable standard carrying a rotary support for the box-bottom and having a locking-bolt operated by a spring-actuated lever, a paste-cup mounted on an adjustable support and having a curved bottom plate, its ends detached from the walls of the cup, a set-screw bearing against the exit end of the said plate to adjust the width of the exit-opening, a support for the roll or coil from which the strip is taken, and an adjustable tension device acting upon said roll, 40 substantially as described.

In testimony whereof I have affixed my signature in presence of two witnesses.
